(57) **CLAIM**

We claim, the ornamental design for a confection, as shown and described.

DESCRIPTION

FIG. 1 is a perspective view of a confection, showing our new design in a first exemplary embodiment;

FIG. 2 is a top plan view of the embodiment shown in FIG. 1;

FIG. 3 is a bottom plan view of the embodiment shown in FIG. 1;

FIG. 4 is a side elevation view of the embodiment shown in FIG. 1;

FIG. 5 is another side elevation view of the embodiment shown in FIG. 1;

FIG. 6 is a front elevation view of the embodiment shown in FIG. 1;

FIG. 7 is a back elevation view of the embodiment shown in FIG. 1;

FIG. 8 is a perspective view of a confection, showing our new design in a second exemplary embodiment;

FIG. 9 is a top plan view of the embodiment shown in FIG. 8;

FIG. 10 is a bottom plan view of the embodiment shown in FIG. 8;

FIG. 11 is a side elevation view of the embodiment shown in FIG. 8;

FIG. 12 is another side elevation view of the embodiment shown in FIG. 8;

FIG. 13 is a front elevation view of the embodiment shown in FIG. 8;

FIG. 14 is a back elevation view of the embodiment shown in FIG. 8;

FIG. 15 is a perspective view of a confection, showing our new design in a third exemplary embodiment;

FIG. 16 is a top plan view of the embodiment shown in FIG. 15;

FIG. 17 is a bottom plan view of the embodiment shown in FIG. 15;

FIG. 18 is a side elevation view of the embodiment shown in FIG. 15;

FIG. 19 is another side elevation view of the embodiment shown in FIG. 15;

FIG. 20 is a front elevation view of the embodiment shown in FIG. 15;

FIG. 21 is a back elevation view of the embodiment shown in FIG. 15;

FIG. 22 is a perspective view of a confection, showing our new design in a fourth exemplary embodiment;

FIG. 23 is a top plan view of the embodiment shown in FIG. 22;

(Continued)

FIG. 24 is a bottom plan view of the embodiment shown in FIG. 22;

FIG. 25 is a side elevation view of the embodiment shown in FIG. 22;

FIG. 26 is another side elevation view of the embodiment shown in FIG. 22;

FIG. 27 is a front elevation view of the embodiment shown in FIG. 22; and,

FIG. 28 is a back elevation view of the embodiment shown in FIG. 22.

The lighter stipple shading shown in FIGS. 1-7 and 15-21 represent a contrast in appearance between the stippled layer and the non-stippled layers.

The heavier stipple shading shown in FIGS. 8-14 and 22-28 represents contrast in appearance between the stippled region and non-stippled region.

The lighter stipple shading in FIGS. 1-7 and 15-21 and the heavier stipple shading in FIGS. 8-14 and 22-28 shown in the drawings represent a contrasting appearance.
